the invention is to provide a stirrup which is associated with the lower portions of the harness frames, and which is connected to the jack strap, so that the stirrup is held in a straight line with the jack strap, and the strap is held in a straight line with the treadles, so that the strap does not swing when the jack strap is held in a straight line.

UNITED STATES PATENT OFFICE

2,445,065

JACK STRAP AND STIRRUP

Fred A. Hamilton, Easley, S. C., assignor of one-half to Jerry P. Lesley, Easley, S. C.

Application May 15, 1946, Serial No. 669,887

4 Claims. (Cl. 139—83)

1

2

This invention relates to an improved stirrup for connecting the treadles of a loom to the jack strap, which is associated with the lower portions of the harness frames.

Heretofore, the stirrups disposed on the treadles have extended upwardly a substantial distance, and have secured thereto, by means of a bolt and thumb nut, the two ends of a leather strap, which extends upwardly and passes through a slot in the jack stick. As is well known, the treadles of the loom move part of the harness frames downwardly and cause other frames to move upwardly to form a shed in the warp. It very often happens that the jack stick, when in lowered position, will engage the thumb nut on the stirrup associated with the jack strap connected to the harness frame, which is in raised position. This causes a notch to be cut from the lower edge of the jack stick, and this notch soon deepens to the point where the jack stick is weakened to the point where it must be replaced.

In the type of strap and stirrup heretofore used, there has been a stirrup similar to the one shown in the drawings, except that the transverse portion at the top was not offset, and around this transverse portion was doubled one end of the strap, and above the transverse portion, there were two coinciding holes in the strap, through which a bolt was placed, and this bolt penetrated the slot in the free end of the strap, and a suitable plate on the bolt was confined by a thumb nut. This placed the thumb nut at a very much greater distance above the treadle than in the present style of stirrup. The old type allowed stretching of the strap between the stirrup and the bolt, and would allow what is called "riding up" resulting in the nut on the bolt striking the jack stick and breaking of the jack strap, and cutting a large gap in the lower edge of the jack stick.

With the present type of stirrup, the jack straps wear much longer. Practically all jack straps wear out where they loop around the old type stirrup, and very little wear occurs where the strap goes through the slot in the jack stick. By clamping the jack strap at the stirrup, as in the present invention, all wear at the connection point between the top of the stirrup and the jack strap is eliminated.

The present invention also eliminates "swinging" and wearing of the stirrup on the treadle by being held in a straight line by the stiffness of the jack strap. Another important feature of the invention is that these jack straps are usually made of a good quality of leather, and the pres-

ent invention saves approximately four inches of leather on each jack strap.

It is an object of this invention to provide a stirrup of much shorter length than has heretofore been used, and having a transverse portion disposed at a much lower point than has heretofore been the custom, and this transverse portion is provided with a bolt and a thumb nut, so that the two ends of the jack strap can be adjusted, one of the ends having a suitable slot therein, and thus the bolt with the thumb nut thereon is lowered to a point sufficiently close to the treadles to prevent it being engaged by a lowered jack stick, when its associated jack stick and harness frame is in raised position.

Another important advantage of the present invention is that in the old type of connection, there was a stirrup and a separate clamp disposed above the stirrup. In the present invention, the stirrup and clamp are combined, so it is a combination stirrup and clamp, thus lowering the position of the clamp substantially and thus causing the bolt and nut associated with the clamp to be down close enough to the treadle so that the bolt will not engage a lowered jack stick.

Some of the objects of the invention having been stated, other objects will appear as the description proceeds, when taken in connection with the accompanying drawings, in which:

30. Figure 1 is an elevation of a portion of a loom and showing two harness frames, one in elevated and one in lowered position;

Figure 2 is an enlarged detail and showing in elevation the stirrup and its associated strap;

35. Figure 3 is a vertical sectional view taken along the line 3—3 in Figure 2;

Figure 4 is a vertical sectional view taken along the line 4—4 in Figure 1;

40. Figure 5 is an elevation of the stirrup disassociated from the strap and the bolt and square washer normally associated therewith;

Figure 6 is an elevation of one of the straps associated with the stirrups and with the jack sticks.

Referring more specifically to the drawings, the numerals 10 and 11 indicate a pair of harness frames, having heddles 12 and 13 therein, each heddle having an eye, such as 15 and 16, therein and the upper end of harness frame 10 is supported by suitable straps 18 and 19 secured to and adapted to be wound around suitable rollers 20 and 21, disposed on an oscillatable shaft 22, which is suitably mounted in the loom frame by means, not shown, and suitably connected to the

treadle operating means, to be described, to synchronize and operate therewith.

The harness frame 11 is supported by suitable straps 24 and 25, which are likewise secured to and adapted to be wound around suitable members 26 and 27 secured on the shaft 22.

The lower end of harness frame 10 has suitable U members 30 and 31 secured thereto, to which jack hooks 32 and 33 are connected, which in turn are mounted in eye bolts 34 and 35 secured in a jack stick 36.

The harness frame 11 likewise has suitable U members 40 secured near each end thereof in the same manner as U members 30 and 31, to which hooks 41 and 42 are secured, which are adapted to hook in eye bolts 43 and 44 secured in a jack stick 45.

The jack sticks 36 and 45 have holes 46 and 47 respectively therein through which passes a strap member, such as leather straps 48. These strap members 48 at their lower ends have a suitable hole 49 therein, which is penetrated by a bolt 50 mounted in a hole 46 in a transverse portion 51 of a stirrup 52, which has a lower transverse portion 53 which is adapted to hook in one of the notches 54 in one of the stirrup levers 55. The other end of the strap member 48 has an elongated slot 55, and after the strap member 48 passes through one of the slots 46 or 47, it is dropped down and passed over the bolt 50 and a rectangular washer 57 is placed against the same, and then a thumb nut 58 is driven home on the bolt 50 to clamp the free end of the strap 48 in position to thus regulate the overall length of the strap 48 between the bolt 50 and the slot 46 or 47. The treadles 55 are pivoted, as at 60, in a conventional manner and have conventional rollers 61 therein, which are adapted to be contacted by suitable cams 62 mounted on cam shaft 63, which is driven in a conventional manner in timed relation to the shaft 22 and since this movement is conventional further description is not deemed necessary.

It is thus seen that we have provided a jack strap connection for a new type of stirrup for connecting the lower ends of the jack straps to the treadles, which are disposed low enough so as not to be engaged by the jack stick, as the harness frame moves one to uppermost position and one to lowermost position.

In the drawings and specification, there has been set forth a preferred embodiment of the invention, and although specific terms have been employed, they are used in a generic and descriptive sense only, and not for purposes of limitation, the scope of the invention being defined in the claims.

I claim:

1. A stirrup for connecting the treadles of a loom with the jack stick comprising a member having a U-shaped portion whose lower end is adapted to fit into one of the notches in the lower surface of the treadles of the loom, and having its upper end closed by a transverse portion and provided with a hole, a bolt mounted in said hole, a jack strap having a hole in one end thereof penetrated by said bolt, said jack strap having an elongated slot in its other end, the jack strap being adapted to be passed through a suitable slot in the jack stick and to have its free end penetrated by said bolt, a washer adapted to fit around said bolt and against the free end of said jack strap, and a thumb nut threadably

secured on said bolt for forcing said washer against the free end of said strap for clamping the same in adjusted position.

2. In a loom having harness frames and treadles for raising and lowering the harness frames, each harness frame having secured to its lower edge a jack stick, each jack stick having a slot therethrough, a jack strap adapted to be passed through the slot and having its two ends extending downwardly, one of the ends of said strap having a hole therethrough, a stirrup member having a lower transverse portion adapted to hook beneath a treadle and having an upper transverse portion penetrated by a bolt, said bolt being adapted to penetrate the hole in one end of said jack strap, the other end of said jack strap having an elongated slot therein adapted to fit over said bolt, and a washer on said bolt and a nut on said bolt for clampingly engaging the free end of the jack strap and holding it in adjusted position.

3. In a loom having harness frames and treadles for raising and lowering the harness frames, each harness frame having secured to its lower edge a jack stick, each jack stick having a slot therethrough, a jack strap adapted to be passed through the slot and having its two ends extending downwardly, one of the ends of said strap having a hole therethrough, a stirrup member having a lower transverse portion adapted to hook beneath a treadle and having an upper transverse portion penetrated by a bolt, said bolt being adapted to penetrate the hole in one end of said jack strap, the other end of said jack strap having an elongated slot therein adapted to fit over said bolt, a washer on said bolt and a nut on said bolt for clampingly engaging the free end of the jack strap and holding it in adjusted position, the position of said bolt being low enough so that the nut thereon will not be engaged by a lowered jack stick, when the nut is moved to raised position by the raising of the other harness frame.

4. In a loom having jack sticks, treadles, and jack straps, a stirrup connecting the treadles to the jack sticks of the loom, said stirrup having a transverse lower portion adapted to fit against the lower surface of the treadles, said stirrup projecting upwardly and outwardly on each side of a treadle and having a transverse portion, the transverse portion being provided with a hole and bolt mounted in said hole and penetrating the ends of the jack strap after the jack strap has been passed through a suitable slot in the jack stick, one end of the jack strap having an elongated slot extending longitudinally of the jack strap and through which the bolt passes, and a nut on said bolt for clampingly engaging the two ends of the jack strap and holding it in adjusted position.
